(57) **CLAIM**

The ornamental design for a combined pet bed and pillow with attached blanket, as shown and described.

DESCRIPTION

FIG. 1 is an exploded top front perspective view of a combined pet bed and pillow with attached blanket;

FIG. 2 is a top front perspective view thereof;

FIG. 3 is a top view of FIG. 2;

FIG. 4 is a front view of FIG. 2, the left, right, and back views are identical to the front view shown;

FIG. 5 is a top front perspective view of the bed seen in FIG. 1;

FIG. 6 is a bottom front perspective view of FIG. 5;

FIG. 7 is a front view of FIG. 5, the left, right, and back views are identical to the front view shown;

FIG. 8 is a bottom view of FIG. 5;

FIG. 9 is a top view of FIG. 5;

FIG. 10 is a top front perspective view of the pillow with attached blanket seen in FIG. 1;

FIG. 11 is a bottom front perspective view of FIG. 10;

FIG. 12 is a front view of FIG. 10, the left, right, and back views are identical to the front view shown.

FIG. 13 is a bottom view of FIG. 10; and,

FIG. 14 is a top view of FIG. 10.

The broken lines are for illustration only and form no part of the claimed design.

1 Claim, 14 Drawing Sheets
